ABSTRACT

A yarn drive roller having a two-part co-planar drive surface, one part being metallic or of other wear resistant material and the other being a frictional drive surface of synthetic material, rubber, or other composition.

FIG. 1

FIG. 3

FIG. 2

FIG. 4

YARN DRIVE ROLLER

The present invention relates to a yarn drive roller, such as is used on false twisting machines in the texturizing of synthetic yarns.

BACKGROUND OF THE INVENTION

The texturizing of synthetic yarns is carried out on what is known as a "false twisting machine" in which the yarn is processed at high speeds. Such machines employ a large number of drive rollers, as many as 200 such rollers being employed on some such machines. The yarn is wrapped around the drive rollers for several turns via an idler pulley and, by virtue of the very high speeds of operation, such rollers are subjected to very heavy wear. In fact, due to the abrasive qualities of the synthetic yarns, the drive surfaces of the drive rollers quickly become worn and indented, and alternate grooves and ridges appear in such surface which adversely affects the yarn process carried out by the machine, and impairs the quality of the finished yarn. At the present time, such drive rollers are required to provide a certain amount of friction as between the surface of the roller and the yarn, so as to ensure positive drive of the yarn. In addition, by virtue of the fact that the yarn is wrapped around the roller and idler several times, it tends to bite into the roller surface. The required degree of friction is at present produced by the employment of a so-called tire formed of tubular polyurethane or rubber material slipped onto the outside of the roller, and machined to a predetermined size. When the polyurethane or rubber tires become worn, it is then necessary to remove the rollers from the machine, and then to strip off the tires, and replace them with new ones, after which they are machined to size. This is obviously a fairly time consuming procedure, and is wasteful both in the actual cost of replacement, and also in the down time of the machine involved.

BRIEF SUMMARY OF THE INVENTION

The invention therefore seeks to provide an improved drive roller, designed to provide the required frictional drive for the yarn, and designed to withstand continued heavy duty usage with a minimum of wear, and in addition, which is of such a design that it can be readily serviced without the necessity for repeatedly removing the rollers from the machine.

More particularly the invention seeks to provide a yarn drive roller having a two-part co-planar drive surface one part being metallic or of other wear resistant material and the other being a frictional drive surface of synthetic material, rubber, or other composition.

More particularly, it is an objective of the invention to provide a replaceable drum for such drive rollers comprising a thin walled metallic sleeve adapted to slip over the roller, and an exterior tire fitted around such sleeve, thereby simplifying the replacement of the original tire.

More particularly, it is an objective of the present invention to provide such a drum formed of metal, one end of which is enlarged to the diameter of the drive surface of the roller and provides a highly wear resistant metal drive band for engagement by the first turn of the yarn, and the remainder of the sleeve being of reduced diameter, and carrying a tire of polyurethane, rubber or composition of the same diameter as the

metal drive band to provide the required amount of friction.

The foregoing and other objectives will become apparent from the following description of a preferred embodiment of the invention which is given here by way of example only with reference to the following drawings.

BRIEF DESCRIPTION OF THE DRAWINGS

10 FIG. 1 is a perspective illustration of a portion of a false twist machine showing a yarn drive roller mounted in position thereon;

15 FIG. 2 is a sectional side elevational view of the roller shown with the replaceable drum in exploded form,

15 FIG. 3 is a greatly enlarged sectional illustration along the line 3-3 of FIG. 2, and,

20 FIG. 4 is a sectional side elevation of a further embodiment.

DETAILED DESCRIPTION OF THE PREFERRED EMBODIMENT

Referring now to FIG. 1, this illustration discloses only a very small portion of a false twisting machine that is to say the portion comprising one of the many yarn drive roller assemblies, as it is mounted on the machine. This assembly is in fact mounted on a vertical pivot, on the machine, and can be swung to an fro between two positions as desired, in a manner well known per se in association with such machine. Obviously, the entire details of the false twisting machine are not relevant for the purposes of the present invention, and are therefore omitted for the sake of clarity. There will of course be many such drive roller assemblies, located at various points on the machine.

Again referring to FIG. 1, the yarn drive roller assembly will be seen to comprise a complex plastic moulded mounting member 10 provided with a vertical pivot opening 11 therethrough for mounting on a false twisting machine in a pivotal manner (the details of which are omitted for the sake of clarity). The yarn drive roller itself is shown as 12, and is rotatably mounted on the mounting member 10 by any suitable bearing means not shown, so that the same may be driven at

40 high rotational speed. An angled guide roller 13 is rotatably mounted on the mounting member 10 more or less vertically below the drive roller 12. The guide roller 13 is set at a slight angle to the axis of rotation of the drive roller 12, whereby to guide the turns of the

50 yarn around the drive roller 12, and keep them spaced in a more or less predetermined spaced relation so that they do not become tangled together. A yarn guide shoe 14 is provided to one side of the mounting member 10 for guiding the first turn of yarn onto the drive roller 12. The drive roller 12 is provided with a drive gear 15 by means of which the drive roller 12 may be engaged with a power operated gear drive in the false twisting machine (not shown) and thereby driven at high speeds during operation of the machine.

55 It will of course be understood that the mounting member 10, guide roller 13, and the general configuration of typical yarn drive rollers are known per se and form no part of the present invention.

60 The yarn drive roller 12 according to this preferred embodiment of the invention comprises the generally cylindrical roller body portion 16, and the replaceable drum member 17 which are separable from one an-

other and are held together by the screw 18 as will be described below.

With reference now to FIGS. 2 and 3, it will be seen that the roller body portion 16 is of generally cylindrical shape having four interior rib members 19, one of which is provided with a screw threaded recess 20 for reception of screw 18 therein. The exterior of the roller body 16, according to the practice of the present invention is stepped to provide a shoulder 21 thereon for purposes to be described, and is provided with any suitable form of bearing housing such as the sleeve member 22 at its inner end.

The replaceable drum member 17 is provided around the body 16 and will be seen to comprise an inner generally cylindrical metallic sleeve member 23 having an enlarged portion indicated as 24 and defining an inner shoulder 25 for abuttment against the shoulder 21 on the roller body portion 16. The sleeve 23 is provided with an enlarged metallic drive band or surface 26 and an outer tire mounting surface 27 of reduced diameter in relation to the diameter of the band portion 26. A frictional drive tire member 28 formed of rubber, composition or synthetic frictional material, in this case being a cylindrical portion of polyurethane material, is bonded in place as by the adhesive layer 29. The outer surfaces of the tire 28 and the annular metallic drive surface 26 are co-planar to provide a smooth continuous surface for driving of the yarn at high speeds.

Preferably according to the invention the whole of the sleeve 23 is machined from aluminum and the annular metallic surface 26 is anodized by a technique known as "hard anodizing" which provides a highly wear resistant surface which has been found according to the invention to have properties which are peculiarly suitable for the high speed driving of synthetic yarns. Preferably, the first turn or wrap of the yarn will pass around the metallic drive surface 26, which is thereby subjected to the heaviest wearing stresses and the remaining wraps or turns pass around the frictional tire 28.

As shown in FIG. 2, the sleeve 23 may be slipped over the roller body member 16 until the shoulder 25 abuts against the shoulder 21, after which the screw 18 can be inserted into the recess 20 and tightened up thereby fastening the drum 17 firmly in position.

In operation, the yarn will pass upwardly through the guide shoe 14 and be wrapped around the replaceable drum 17 with the first turn passing around the metallic drive surface 26 and then downwardly around the guide roller 13 and then upwardly and downwardly another three times around the tire 28. In this way, during use the first turn is carried on the drive surface 26 which is highly resistant to abrasion, and the remainder of the turns are carried on the tire 28. Obviously, the frictional properties of the tire 28 are somewhat greater than the drivesurface 26 and are designed so as to provide sufficient friction against the turns of the yarn as to drive them with a minimum of slippage.

It will thus be noted that the invention provides in a yarn drive roller, a two part drive surface, comprising a hard wear resistant band portion, and a frictional drive surface adjacent thereto, said band portion and the said drive surface being co-planar and thus permitting the yarn to be wrapped several times around the roller, with the first such wrap or turn being wound around the surface of the wear resistant band portion, and the remaining such wraps or turns being wound

around the friction drive surface. Obviously, such a yarn drive roller may be manufactured in a variety of ways. For example, the yarn drive roller could be manufactured with the entire drive roller machined out of a single casting, with the hard wear resistant drive band being machined out of a portion of the casting integral with the rest of the roller, and the frictional tire being slipped on a portion of the roller provided for the purpose. Such a roller would of course have the disadvantage that the entire roller would have to be removed when it was desired to replace the frictional tire portion, but this might possibly be acceptable in some circumstances. On the other hand, it would be possible to manufacture the invention in accordance with the alternative embodiment as shown in FIG. 4. In this embodiment, a replacement drum member 17a will be seen to comprise a sleeve 23a manufactured with an interior abutment member 25a substantially as in the embodiment of FIGS. 1 to 3, but the outer surface of such sleeve 23a is cylindrical throughout its length, unlike the embodiment of FIGS. 1 to 3. A hard metallic drive band or wear resistant surface 26a is provided by means of a separate cylindrical annular member fitting around the exterior of one end of the sleeve 23a, and secured thereto by any suitable means such as by press fitting, adhesives or the like. A frictional tire 28a of any suitable frictional material such as that described above, is provided over the exterior of the remainder of the sleeve 23a, the exterior of the band 26a and the tire 28a being co-planar to provide a continuous surface for the yarn drive roller 12.

Obviously, this brief description of other modifications or alternate methods of achieving the result according to the invention is by no means exhaustive. For example, the tire 28 could itself be mounted on a separate metallic sleeve, while the wear surface or band portion 26 is machined integrally with the yarn drive roller itself, and may in fact constitute merely an enlargement of the band extending adjacent to the shoulder 21. In this way, the tire 28 would be replaceable, without disturbing the wear resistant band. However, this latter alternate method of constructing the yarn drive roller according to the invention may not be quite so desireable since even though the tire 28 is replaceable, it may be extremely difficult to manufacture it to sufficiently close tolerances to ensure that it is always perfectly co-planar with the surface of the wear resistant band, and it is generally speaking considered preferable to manufacture the two together, as described above.

A further unique property of the drive roller according to the invention which has become apparent after extended testing is the fact by virtue of the combination of an anodized metallic band surface 26 and a frictional tire 28, the yarn processed is found to have a much higher quality than that processed on a standard drive roller having a polyurethane or other frictional drive tire extending right across its surface. As yet, no explanation has been found for this unusual result, but it is believed to be due to the fact that as the first turn or wrap of yarn passes sideways across the surface of the band surface 26, it is smoothed and polished in a manner not hitherto possible using standard polyurethane tires right across the surface of the drive roller.

The foregoing is a description of a preferred embodiment of the invention which is given here by way of example only. The invention is not to be taken as limited

to any of the specific features described, but comprehends all such variations thereof as come within the scope of the appended claims.

The embodiments of the invention in which an exclusive property or privilege is claimed are defined as follows:

1. A yarn drive roller for use on yarn processing machines, of the type wherein the roller is driven by the machine and a plurality of turns of yarn are wound therearound, the yarn being frictionally engaged by the roller which is thereby subjected to a high rate of wear, said drive roller comprising:

roller body means rotatably mountable on said machine,

a two part drive surface on said roller body means, said drive surface being cylindrical and having two ends and being formed with two surface portions meeting at a junction point intermediate said two ends, a first surface part extending from one said end to said junction point being formed of hard smooth material, resistant to wear by said yarn and a second surface part extending from said junction point to said other and being formed of frictional material having less resistance to wear by said yarn than said first said surface part whereby yarn wound around said drive surface may run initially on said first surface portion and subsequently on said frictional surface, the portions of yarn on said frictional surface being frictionally engaged for positively driving said yarn, with said first surface portion taking the initial load;

a drum member adapted to fit snugly around said roller body means for rotation therewith in unison, said two part drive surface being formed on the exterior surface of said drum member, and releasable means securing said drum member on said body.

2. A yarn drive roller as claimed in claim 1 including yarn guide means mounted adjacent said roller body

means, and arranged and oriented to guide a first turn of said yarn onto said first surface part.

3. A yarn drive roller as claimed in claim 1 wherein said first surface part is formed by a metallic member, and wherein said second surface part is formed by a sleeve of rubber.

4. A yarn drive roller as claimed in claim 1 including abutment means formed on the surface of said roller body means, and complementary mating abutment means formed on an inner surface of said releaseable drum, said abutment means adapted to abut with one another and limit interengagement between said roller body means and said drum member, and including releasable retaining means interengageable between said roller body means and said drum member to secure the same in position as aforesaid.

5. A yarn drive roller as claimed in claim 1 wherein said first surface part is formed of an annular band of metal formed separately from said roller body, and fastened thereto in predetermined location, and wherein said second surface part is formed of a generally cylindrical sleeve member formed of frictional material, having one end abutting against said cylindrical band member, and having a surface co-planar with the surface of said cylindrical band member whereby to define a continuous two part drive surface on said roller body as aforesaid.

6. A yarn drive roller as claimed in claim 1 wherein said first surface part is formed of anodized aluminum.

7. A yarn drive roller as claimed in claim 1 wherein said second surface part is formed by a sleeve of synthetic rubber.

8. A yarn drive roller as claimed in claim 1 wherein said second surface part is formed by a sleeve of synthetic plastic material.
